RADIO APPARATUS

Merion J. Huggins, Upper Saddle River, N. J.

Application July 10, 1931, Serial No. 549,847

17 Claims. (Cl. 250—20)

This invention relates to control means for radio apparatus and particularly to means to operate variable condensers or other tuning means to synchronize or tune the receiving circuit of the apparatus to resonance with the incoming transmitted radio frequencies, and it is an object of the invention to provide means to actuate the tuning means to positively and accurately tune in predetermined radio frequencies at a place remote to the radio apparatus.

It is another object of the invention to provide means connected in circuit with the actuating means for the tuning means whereby said actuating means is operative at predetermined intervals or periods of time to tune or synchronize the electric circuit of the receiving apparatus to resonance with preselected transmitted radio frequencies.

In the embodiment of the invention illustrated there is provided a pair of solenoids mounted relative to a radio apparatus and each solenoid adapted to actuate a separate armature, both armatures being operatively connected to the adjustable elements of variable condensers and movable under the influence of their respective solenoids in opposite directions corresponding to the differential energization of the solenoids, and means is provided to retain the armatures in actuated positions electromagnetically controlled by circuit breaking means actuated by the movements of the armatures. Periodically actuated means is interposed in the circuit of the solenoids to cut out proportional amounts of electric resistance means to predeterminedly and differentially energize the solenoids to actuate the armatures to position the adjustable elements of the variable condensers to resonance with a selected transmitted frequency at a predetermined period of time.

In the drawings accompanying and forming a part of this application, Figure 1 is an elevational view of the actuating and retaining means connected to a variable condenser and showing diagrammatically the electric circuit and connection thereof with regulatable means therefor.

Figure 2 is a side elevation of one of the circuit regulatable means shown in Figure 1.

Figure 3 is a diagrammatic arrangement of the parts shown in Figure 1 and showing the electric connections thereof.

Figure 4 is an end view of the actuating and retaining means looking at the left of Figure 1.

Figure 5 is a side view of the solenoid and armature looking at the left of Figure 1.

Figure 6 is a view similar to Figure 5 showing

the solenoid and armature at the right of Figure 1, and the adjustable electrode of the variable condenser.

Figure 7 is a view similar to Figure 1 on a reduced scale showing periodically actuated means interposed in the circuit of the actuating and retaining means.

Figure 8 is a diagrammatic arrangement of the parts shown in Figure 7.

Figure 9 is an elevational view of an electromagnetic circuit maker of a series associated with the periodically actuated means shown in Figure 7; and

Figure 10 is a cross sectional view of the periodically actuated means shown in Figure 7.

In carrying out the embodiment of the invention illustrated the actuating means may be wholly or partly mounted adjacent to or within the cabinet of the radio receiving apparatus and connected to the means to synchronize the receiving circuit of the apparatus to resonance with the transmitted radio frequencies which in the present instance embodies a condenser or condensers in the form of a series of plate electrodes 11

movably mounted in spaced and interposed relation to a series of plate electrodes 12 fixedly carried by a dielectric support 13 mounted on a base 14 of the radio receiving apparatus. The actuating means comprises a pair of arcuate

armatures in the form of split rings 15, 16 of 85 magnetizable or polarized material extending through an arc of more than 180 degrees and preferably of tapered formation, said armatures in the present instance being mounted coaxially

on the support of the adjustable electrode to 90 rotate about their axes and transmit the movement thereof to the movable electrodes 11 by arms 17 having a boss 18 at one end coaxially of the armatures for the engagement of and fixed on

a shaft 19 rotatably mounted in a pair of spaced standards 20 fixed to and extended upwardly from the base 14 adjacent the bosses 18, the plates of the movable electrode 11 also being carried on

said shaft 19 and maintained in spaced relation to each other by a boss 21 fixed on one end of the shaft. The free ends of the arms 17 are extended laterally toward the opposite arm and the rings 15, 16 secured to said arm extensions adjacent the ends of greatest width, as at 22 in

Figure 1, with the reduced ends of the rings extended in opposite directions so that the gaps of the rings are positioned at approximately opposite sides of the shaft 19, for a purpose to be hereinafter described.

The armature rings are adapted to be rotatably

5 moved in opposite directions to a multiplicity of stable positions under the influence of the magnetic forces of magnetic fields generated by coils or solenoids connected in circuit with a source 10 of electricity preferably independent of the circuit or circuits of the radio receiving apparatus, the generated magnetic forces being adapted to be varied relative to each other. For this purpose there is provided a pair of oppositely wound coils 15 23, 24 wound upon spools mounted on the base 14, as at 25, said coils being in the nature of solenoids and the rings 15, 16 as armatures movable in the cores 23, 24, respectively, whereby the greater energization of one solenoid over the 20 other, such as coil 23, will rotate shaft 19 in a direction to move the arms 17 forward, looking at Figure 1, in the direction of the arrow *a* in Figure 5, due to the location of the bulk of material of the armature 15 relative to the arm 17 25 and the weakness generated by the magnetic field of solenoid 24 thereby permitting free movement of the armature 16 and therewith the electrode carrying shaft 19.

30 The coils 23, 24 are energized from a source of electricity, as a battery B, to one side of which one terminal 26, 27 of coils 23, 24, respectively, are connected, by a conductor 28. The coils are differentially energized relative to each other by cutting out or connecting in of variable amounts 35 of electric resistance, in the form of coils 29, 30, one terminal of resistance 29 being connected by a conductor 31 to terminal 32 of solenoid 23 opposite to the terminal 26, and one terminal of resistance 30 connected by conductor 33 to terminal 34 of solenoid 24 opposite the terminal 27 of said 40 solenoid. Different portions of each resistance are adapted to be automatically connected to the side of the battery B opposite to the side connected with the terminals 26, 27 of the solenoids to differentially energize the solenoids. This automatic connecting of different amounts of the resistances into and out of the circuits of the solenoids is accomplished by a series of contact members 35 each comprising a resilient plate 45 mounted at one end on a conductor member 36 fixed to and extended along a marginal portion of a support 37 of non-conducting material by screws 38 passed through perforations in the contacts 35 and the conductor member 36 and threaded into 50 the support 37, to permit the free ends of the contacts 35 to be actuated into engagement with a pair of contacts 39, 40 mounted in a series on the support 37 and connected to the solenoids either directly or through the resistance coils 29, 30. To 55 complete the circuit the contacts 35 are connected to the battery B through the conductor member 36 by a conductor 41.

60 In the present instance the contacts 35, 39, 40 are arranged whereby the receiving circuit of the radio apparatus is capable of being tuned to resonance with six different predetermined transmitted radio frequencies. To accomplish this there is provided six of the contacts 35 together with six pairs of contacts 39, 40 and the 65 contacts are divided into two sets of three actuating contacts 35 each, with each set connected to a solenoid to vary the energization thereof through the resistances 29, 30, each resistance comprising three coils connected in series, as 70 shown in Figures 1 and 3. One side of the contacts of each set is directly connected without passing through the resistance coils to the solenoid opposite to the solenoid the connected set is adapted to vary the energization thereof so 75 that upon the actuation of a contact of either

set one of the solenoids is fully energized. In the present instance, looking at Figures 1 and 3, the contacts 40 of the left hand set of contacts are directly connected to the terminal 34 of the solenoid 24 by a conductor 42 connected to the contacts 40 and to the conductor 33 beyond the circuit of the resistance coils 30. The contacts 39 of the right hand set of contacts are connected in circuit with the terminal 32 of the solenoid 23 by conductor 43 connected to the contacts 39 and conductor 31 outside the circuit of the resistance coils 29.

80 The actuation of one of the contacts 35 of the left hand series will effect rotation of the shaft in an anti-clockwise direction, as viewed in Figures 3 to 6, inclusive, as solenoid 24 is fully energized and the rotation of the shaft in the direction of the movement of the wide portion of the armature 16 into the core of said solenoid is limited by the low energization of the solenoid 23 due to the passage of the electric current through the series of resistance coils 29, the greater the amount of the resistance connected into the circuit the greater will be the extent of 85 rotation of the shaft 19 in anti-clockwise direction and the actuation of the movable electrode plates 11 to one of their extreme positions. The contact 39 of the end contact 35 of the left hand set is connected by conductor 44 to the side of the resistance coils 29 opposite to the side connected to the terminal 32 of coil 23 so that upon 90 the actuation of said end contact the armature 16 is moved to its extreme position with the widest portion thereof within the coil 24, and the actuation of the intermediate contact member 35 of the left hand set will position the armature with the wide portion out of the coil 24 due to the increase in the energization of the solenoid 23 as the end section of the resistance coils 29 is cut 95 out of the circuit by contact 39 of said intermediate contact 35 being connected to the intermediate coil of series 29 by a conductor 45. The initial actuating position of armature 16 is effected by actuating the innermost contact 35 of the left hand set of contacts whereby the movable electrode plates 11 are actuated to one of their intermediate positions, when the contact 39 of the innermost contacts 35 of the left hand 100 series of contacts is connected by a conductor 46 through the end coil of the series 29 connected to the terminal 32 of solenoid 23.

105 The actuation of any one of the contacts 35 of the right hand series will effect the full energization of the solenoid 23 and render the same as the actuating solenoid causing the rotation 110 of the shaft 19 in a clockwise direction, as viewed in Figures 3 to 6, inclusive, under the limiting influence of armature 16 due to the controlling energization of the solenoid 24 through the series of resistance coils 30. The actuation of contact member 35 of the innermost contacts of the right hand series will position the armature 15 in its initial actuating position, as shown in Figure 5, and the electrode plates 11 in the other of their intermediate positions, and the actuation of the 115 other contact members 35 of said right hand set of contacts will proportionally decrease the energization of the solenoid 24 by connecting the contact members 40 of said contacts through an increasing number of coils of the series of resistance coils 30, commencing from the innermost contacts by conductors 47, 48, 49, leading to the coil connected to the terminal 34 of solenoid 24, the intermediate coil and the end coil, respectively. The actuation of either of the outer contacts 120

tact members 35 will actuate the electrode plates 11 to either of their extreme positions and the actuation of the successive contact members 35 progressively in an inward direction will actuate the electrode plates 11 to their intermediate positions.

To assure the positioning of the electrode plates 11 in predetermined relation to the fixed electrode plates 12 and overcome the momentum of the actuating armature which will have a tendency to rotate the shaft 19 beyond the predetermined position, control or retaining means are provided to stop and hold the shaft against rotation and automatically interrupt or break the circuit of the solenoids. This control means comprises means to stop the rotation of the shaft 19 and independent means to break the circuit and also control the actuation of the stopping means. The stopping means comprises an index member 20 in the form of a wheel or disk 50 fixed on the shaft 19 and arranged about the periphery with a series of notches 51 spaced apart distances equal to the various stages of travel of the armatures as controlled by the contacts 35 and the notches taken from left to right correspond with the respective contacts 35 looking in the same direction in Figure 3. The notches are releasably engaged by an offset end 52' of a detent 52 in the form of an arm of magnetizable material pivotally mounted at the end opposite the offset end on the base 14 by a pin 53 engaged in a boss 54 arranged at said end of the arm and ears 55 extended from the base 14. The arm 52 is yieldingly urged in a direction to engage the offset end 52' with a notch 51 by a spring 56 (Figure 4) coiled about a stem 57 engaged in a perforation 58 in a portion of the arm 52 extended laterally from the offset end 52' and retained therein by a head 59 on said stem, the other end of the stem slidably engaging a perforation in a lateral extension 60 of an arm 60' projected from the adjacent standard 20, with the stem extending beyond the portion 60 and having a finger gripping manipulating knob 61 fixed thereon to facilitate the manual disengagement of the offset 52' from a disk notch 51 to permit adjustment of the electrode 11 by the usual manual means, such as a drum 62 fixed on the shaft 19 and arranged with a peripherally serrated ridge portion 63 and indices 64, as shown in Figures 1 and 7. In the actuation of the tuning means by the solenoids and armatures the pawl 52 is moved away from the notched disk 50 upon the actuation of any of the contacts 35 by an electromagnet 65 carried by an arm 66 extended laterally from the arm 60'. One terminal of the electromagnet is connected by a conductor 67 to the side of the battery B to which the terminals 26, 27 of the solenoids 23, 24 are connected and the opposite terminal of the magnet is electrically connected in open circuit with the opposite side of the battery, as by grounding, by a conductor in electrical connection with shaft 19 through base 14, and the circuit of the magnet adapted to be closed upon the closing of a circuit through either one of the series of contact members 35, 39 and 40, in a manner hereinafter set forth.

To automatically open the circuit of the solenoids 23, 24 when the actuating armature has reached its selected position a cylindrical member 68 of conducting material fixed on shaft 19 is arranged with a series of conductor strips about the periphery thereof equal to the number of contact members 35, in the present instance six in number, and each strip is arranged with an

inset 69 of dielectric material to extend transversely of the strips, said insets 69 being disposed in stepped relation to each other and in radially opposed relation to the notches in disk 50, as shown in Figure 4. Each strip is adapted to be electrically connected to its corresponding contact member 35 upon the actuation of said member into engagement with the contact members 39, 40 by brushes, in the form of resilient conductor strips 70 mounted at one end on a dielectric support 71 fixed to the base 14 in parallel spaced relation thereto, the free end of each strip slidably engaging a strip on the cylindrical member 68, the successive three strips 70 at the left being connected by conductors 72 to a contact member 73 mounted on the support 37 between the contact members 39, 40, of the corresponding contacts commencing at the left of support 37 in Figures 1 and 3. The contact members 73 are arranged so that upon the actuation of a contact member 35, said member 35 engages the contact member 73 before engaging contact members 39, 40, to close the circuit of and energize the electromagnet 65 through brush 70 and cylindrical member 68 to actuate and release the pawl 52 from a notch 51 in disk 50 and permit rotation of the shaft 19 before the energization of solenoids 23, 24 to actuate the armatures 15, 16 by the electrical connection between the contact member 35 and contact members 39, 40, said latter connected simultaneously energizing both solenoids.

It has been found through experiments that the armatures will more readily respond to the energizations of the solenoids when the taper of the armatures extend from the narrow end thereof through an arc of approximately 230° with a portion at the wide end arranged with straight parallel edges and to which portion the solenoid carrying arms 17 are fixed.

In Figures 1 to 6, inclusive, the armatures are shown to be actuated to position when the innermost contact of the set of contacts 35 at the right hand, as shown in Figures 1 and 3, is actuated causing the current to flow from the battery B through the conductor 41, conductor 38 and the contact members 35, 73, along conductor 72 to brush 70' (Figure 1) and the corresponding conducting strip 68' on cylinder 68, and from said member to the electromagnet 65 and battery B, thereby completing the circuit of and energizing the electromagnet 65 to release the detent 52 from engagement with a notch in wheel 50 and permit rotation of the shaft 19. Immediately upon the releasing of the detent 52, the contact member 35 simultaneously engages the contact members 39, 40 and closes the circuit of the solenoids 23, 24 permitting the current to flow from the battery B along conductor 41 to the conductor 38, through the contact members 35, 39, 40 and from contact member 39 the current flows along conductors 43 and 31 to terminal 32 of solenoid 23 thereby fully energizing the same. The circuit is also closed through contact member 40, conductor 47, coil 30' of the series of coils 30 directly connected to solenoid 24, and through said coil by conductor 33 connected to terminal 34 of solenoid 24 whereby resistance to the flow of current from contact member 40 is only slight and the energization of solenoid 24 is proportionally reduced, thereby greatly resisting the actuating movement of the armature 15. When the armatures have attained their adjusted positions the cylinder 68 is correspondingly positioned with a dielectric portion 69' of conducting strip 68' in engagement with the brush 70' preventing the flow of current

through said brush to the cylinder 68 and the electromagnet 65, opening the circuit of said electromagnet and causing the disengagement of the detent pawl 52 from the electromagnet, said pawl being urged by spring 56 into engagement with a notch 51' of disk 50 positioned in alignment with the offset end 52' of the pawl due to the radial arrangement of the notches relative to the corresponding dielectric portions 69. The engagement of offset 52' with a notch 51' will hold the shaft 19 and the armatures 15, 16 against further movement, and prevent the positioning of the electrode 11 beyond the desired adjusted position by the momentum of the actuating armature 15. The circuit of the solenoids is broken by releasing the contact member 35 from the contact members 39, 40 immediately upon the tuning of the receiving circuit to resonance with the desired transmitted radio frequency, which condition is indicated by the audibility of the audio frequency through the usual sound reproducer.

To tune or synchronize the receiving circuit to resonance with any of the other remaining five selected radio frequencies, the contact member 35 corresponding to the desired frequency is actuated into engagement with the contact members 39, 40, 73 when the circuits of the solenoids 23, 24 and electromagnet 65 are completed as all of the brushes 70 except brush 70' are in contact with the conductor strips of cylinder 68 when the parts will again function as heretofore set forth. It is to be understood that any number of series of contacts 35, 39, 40 and 73 may be utilized depending upon the number of selected radio frequencies it is desired to tune in, with a corresponding change in the number of resistance coils in the series of coils 29, 30, the brushes 70 and strips of the cylinder 68.

In Figures 7 to 10, inclusive, there is illustrated means to tune or synchronize the frequency of the circuit of the radio apparatus to resonance with predetermined transmitted radio frequencies at preselected intervals or periods of time, said means being interposed in the circuits of the solenoids 23, 24 and electromagnet 65 and to simplify the illustration of the arrangement of parts the same is shown in connection with radio apparatus only adapted to be tuned to resonance with four predetermined transmitted radio frequencies. Therefore, only four brushes 70 and four corresponding conductor strips on the cylinder 68 are shown, the same being for illustrative purposes only. In utilizing this periodically actuated means all of the parts illustrated in Figures 1 to 6, inclusive, are of the same structure with the exception of the series of contact members 35, said members comprising resilient strips 74 similar to the members 35 but of less width mounted upon a support 75 of U-shape in cross section supported by the legs thereof and having a raised portion 76 extended along one longitudinal marginal edge, as shown in Figure 9, and to which raised portion the contact members are fixed and extended therefrom in spaced and parallel relation to the top of the support with the free ends in juxtaposed relation to contact members 39 and 40 fixed to the longitudinal edge of the support opposite the portion 76 and connected in the circuit of the solenoids 23, 24 through the series of electrical resistance coils 29, 30, each series comprising two coils, one for each predetermined position of the electrode 11. The contact members 74 in the present instance are adapted to be actuated automatically instead of manually by electromagnets 77

mounted on the undersurface of the connecting portion of the support 75 with the coil within the recess portion of the support formed by the legs thereof with the core of the magnet extending through the top of the support below the contact members 74, as shown in Figure 9. The electromagnets are adapted to attract and move the contacts 74 in a downward direction and simultaneously into engagement with the contact members 39, 40. One terminal of each electromagnet 77 is connected by conductors 78 to corresponding brushes 70, and the contact members 74 are also connected in circuit with said brushes by the conductor 78 by leads 79.

A predetermined electromagnet 77 of the series of contacts is periodically connected to the source of electricity B by a periodically actuated device, as at 80 of Figure 7, of suitable structure, such as a spring or electrically operated clock mechanism, detail illustration of which is not deemed to be essential to an understanding of the invention. Said periodically actuated device is adapted to rotate an arm 81 connected thereto as to the arbor carrying the hour indicating hand, and having a permanent magnet 82 fixed to the free end thereof and movable in juxtaposed relation to an annular plate 83 of conducting material electrically connected by conductor 84 to the side of the battery B connected to the terminals 26, 27 of the solenoids 23, 24, respectively. As illustrated in Figure 7 the arm 81 is adapted to be rotated by the clock mechanism and positioned in juxtaposed relation to a flexible finger of a series of fingers 85 of conducting and magnetizable material every fifteen minutes, the fingers 85 being carried by a suitable support 86 of non-conducting material to extend radially toward the center of the annular plate 83 and parallel to said plate, which plate is also mounted on said support 86, as shown at 87 in Figure 7. When the magnetic end of the arm 81 is actuated in alignment with one of the fingers 85, said finger will be moved into engagement with conductor plate 83 under the influence of the magnet 82 and thereby electrically connected to solenoids 23, 24 through conductors 84 and 28, said latter conductor being connected to the battery by the conductor 84. The side of the battery opposite to the side connected to the annular plate 83 is regulatably connected through the cut-out means comprising the cylinder 68, dielectric portions 69 and brushes 70, and the series of contacts 74 to the series of conducting fingers 85. Each individual finger 85 is adapted to be connected in circuit with anyone of the brushes 70 through the corresponding electromagnet 77 to tune or synchronize the receiving circuit of the radio apparatus to resonance with a predetermined transmitted radio frequency at a preselected period of time. This operation is automatically accomplished by a series of electric conducting strips 88 corresponding in number to the number of conducting fingers 85 and mounted at one end on a longitudinal marginal portion 89 of the support 86 to extend in parallel spaced relation to the base 141 portion of said support and connected at the opposite end with a corresponding finger 85, as at 90 in Figures 7 and 10. In the present instance there are seven of such strips and fingers which will be sufficient, when the arm is adapted to be actuated in alignment with separate successive fingers 85 every fifteen minutes, to automatically tune or synchronize the receiving circuit to resonance with a different transmitted radio frequency every fifteen minutes. The strips 150

58 are adapted to be manually and electrically connected to the brushes 70 by conductor members 91 supported on the base of the support 86 in parallel spaced relation to each other and extended transversely of and in spaced relation below the conductor strips 88, there being four of said members 91 in the present instance corresponding to and electrically connected by conductors 92 to the electromagnets 77 and through 10 said electromagnets with the brushes 70. It will readily be seen that the circuit between the battery and the strips 88 is still incompletely and each strip 88 is adapted to be individually connected to anyone of the conducting members 91 by arranging one lateral edge of each strip 88 with semi-circular recesses 93 positioned in alignment with the conductor members 91 and portions of the peripheral wall of perforations in bosses 94 arranged in the conducting members 20 91 relative to the strips 88, as shown in Figure 7, whereby upon the engagement of a pin 95 of conductor material in the perforation of a boss a portion of the pin will engage the recess 93 and electrically connect the engaged member 91 and strip 88 and complete the circuit of the electromagnet 65 by the current flowing from the battery along conductor 67, through the electromagnet 65, cylinder 68, the selected brush 70, through conductor 78, the electromagnet 77 connected to the engaged member 91, and conductor 92 through said member 91 and engaged strip 88, connecting finger 85, and plate 83 with the battery through conductor 84. The circuit of the solenoids is completed through the electromagnet 35 65, cylinder 68, brush 70 and conductor 78 to the contact member 74, which member has been actuated by the energization of the electromagnet 77, as above described, into simultaneous engagement with the contact members 39, 40, and 40 then through the designated coils of the series of coils 29, 30, as hereinbefore described, whereby the solenoids 23, 24 are differentially energized by the current flow through conductors 31, 33, and return to battery B through conductors 28 45 and 84.

It will readily be seen that a varied program of radio transmission may be tuned in during the entire period of time of twenty-four hours by increasing the numbers of the fingers 85 and strips 88 by engaging the pins 95, which pins are arranged with a finger manipulating portion 96, in the desired perforation of members 91, which will actuate the armatures 15, 16 to position the condenser element 11 relative to the condenser element 12 to synchronize the frequency of the audio circuit to resonance with a predetermined transmitted radio frequency which may be designated by the number indicative of the wave length of said frequency on a card or other means attached relative to the members 91.

In the arrangement of the periodically operative control means shown in Figures 7 to 10, inclusive, the actuation of the armatures to the predetermined positions may be controlled independently of the periodically controlled means by a series of contacts comprising flexible contact members 97, equal in number to the number of brushes 70, mounted on a support 98 and electrically connected with each other and the terminals 26, 27 of the solenoids and the battery B through conductor 99 which is a continuation of the conductor 84. Said contact members are normally positioned out of engagement with contact members 100 corresponding in number to the contacts 97 carried by the support 98 and electrical-

ly connected to the electromagnets 77 by conductors 101 connected to the contact members 100 and conductors 92 intermediate the terminals of the electromagnets and the conducting members 91. By these electrical connections of contacts 97, 100 the periodical actuating and controlling means is cut out of the circuits of the electromagnet 65 and the solenoids 23, 24, when the radio apparatus may be tuned in the same manner as the device shown in Figures 1 to 6, inclusive.

It will be obvious that various modifications may be made in construction and arrangement of parts without departing from the scope of the invention, and that portions of the invention may be used without others and come within the scope of the invention.

Having thus described my invention, I claim:

1. In means to tune the receiving circuits of radio apparatus to resonance with transmitted frequencies, a fixed electrode and an electrode spaced from and adjustable relative to the fixed electrode interposed in the circuit of the radio apparatus, electromagnetically operated means connected in a normally open electric circuit with a source of electricity and connected with 100 and adapted to actuate the adjustable electrode relative to the fixed electrode, an index member arranged to conform with a multiplicity of circuit synchronizing positions of the adjustable electrode relative to the fixed electrode connected 105 with and participating in the movement of the electromagnetically operated means, a detent normally urged to engage and co-operate with the index member to retain the electromagnetically operated means and adjustable electrode in 110 predetermined actuated positions, electromagnetically operated means connected in a normally open electric circuit operative upon the closing of the circuit to actuate and hold said detent from the index member to permit actuation of the 115 electromagnetically operated means and the adjustable electrode, selectively operative means to close the circuit of the electromagnetically operated detent actuating means to actuate and hold the detent out of engagement with the index 120 member and close the circuit of and differentially energize the electromagnetically operated electrode actuating means and actuate the adjustable electrode to predetermined synchronized positions relative to the fixed electrode, and means to 125 open the circuit of the electromagnetically operated electrode actuating means and of the electromagnetically operated detent releasing and holding means and permit the latter to assume its index member engaging position to hold the electrode and its operating means against movement.

2. In means to tune the receiving circuits of radio apparatus to resonance with transmitted frequencies, a fixed electrode and an electrode spaced from and adjustable relative to the fixed 135 electrode interposed in the circuit of the radio apparatus, electromagnetically operated means connected in a normally open circuit with a source of electricity and adapted to actuate the adjustable electrode relative to the fixed electrode, a 140 disk having notches spaced about the periphery in conformity with a multiplicity of circuit synchronizing positions of the adjustable electrode relative to the fixed electrode connected with and participating in the movement of the electromagnetically operated means, a detent normally urged toward and releasably engaging a disk notch and thereby holding the electromagnetically operated means and adjustable electrode in predetermined actuated positions, and selectively manually op-

erative means to close the circuit of the electro-magnetically operated detent actuating means to actuate and hold the detent out of engagement with the index member and close the circuit of and differentially energize the electro-magnetically operated electrode actuating means and actuate the adjustable electrode to predetermined synchronized positions relative to the fixed electrode, and means to open the circuit of the electromagnetically operated electrode actuating means and of the electromagnetically operated detent releasing and holding means and permit the latter to assume its index member engaging position to hold the electrode and its operating means against movement.

3. In means to tune the receiving circuits of radio apparatus to resonance with transmitted frequencies, a fixed electrode and an electrode spaced from and adjustable relative to the fixed electrode, both electrodes being interposed in the circuit of the radio apparatus; solenoids connected in circuit with a source of electricity and adapted to be differentially energized to different relative degrees, and arcuate armatures coaxially supported to rotate about their axes within the solenoids and connected with the adjustable electrode to transmit the movement of the armatures thereto, each armature being adapted to remain at all times within the zone of influence of an individual solenoid, thereby preventing critical response of each armature to the energization of its influencing solenoid, and said armatures being moved in opposite directions relative to each other to a multiplicity of stable positions by the relative energization of said solenoids.

4. In means to tune the receiving circuits of radio apparatus to resonance with transmitted frequencies, a fixed electrode and an electrode spaced from and rotatably supported to have adjustment relative to the fixed electrode connected in the circuit of the radio apparatus, solenoids connected in circuit with a source of electricity, arcuate armatures fixedly mounted in coaxial relation upon the support of the adjustable electrode to rotate about their axes and transmit the movement thereof to said electrode, each armature being associated with and movable in and under the influence of an individual solenoid in a direction opposite to the direction of movement of the other armature, electric resistance means having different predetermined amounts thereof connected in circuit with the solenoids to the source of electricity, and circuit making means connected in the circuits of the resistance means with the solenoids selectively operative to connect different predetermined amounts of the resistance means in circuit with the solenoids to differentially energize the solenoids and move the armatures and the adjustable electrode in predetermined directions to a multiplicity of stable positions.

5. In means to tune the receiving circuits of radio apparatus to resonance with transmitted frequencies, a pair of spaced electrodes one of which is rotatably supported and adjustable relative to the other interposed in the circuit of the radio apparatus, a pair of arcuate armatures mounted in coaxial relation on the support of the adjustable electrode to rotate about their axes and transmit the movement thereof to said electrode, a solenoid for and in which each armature is movable and adapted upon the energization thereof to move the armatures in opposite directions under the influence of the solenoids, means normally operative to releasably retain the arma-

tures and adjustable electrode in predetermined positions, electric resistance means having different amounts thereof connected in open circuit with the solenoids to a source of electricity, selectively operative circuit closing means to close the circuit of and connect a predetermined amount of the resistance in circuit therewith to differentially energize the solenoids and move the armatures and thereby the adjustable electrode to selected predetermined stable positions, electromagnetic means connected in circuit with the solenoids operative through the closing of the solenoid circuit to release said retaining means from and permit actuation of the armatures and electrode, and means controlled by the movement of the armatures to selected predetermined position operative to open the circuit of the solenoids and of the retaining means and permit said retaining means to assume its normal position to hold the armatures against movement.

6. In means to tune the receiving circuits of radio apparatus to resonance with transmitted frequencies, a pair of spaced electrodes one electrode being supported to have rotative adjustment relative to the other electrode, a pair of arcuate armatures mounted in coaxial relation on the support of the adjustable electrode to have movement about their axes and transmit the movement thereof to said electrode, a solenoid for each armature connected in circuit with a source of electricity and in which the armatures are adapted to have movement and to be rotated in opposite directions under the influence of the solenoids, means operative to normally releasably retain the armatures and adjustable electrode in predetermined positions, electromagnetic means connected in the circuit of the solenoids with the source of electricity and operative to release the armature retaining means to permit movement of the armatures and adjustable electrode, electric resistance means, circuit closing means connected in the solenoid circuit and different portions of the resistance means to close the circuit of and connect predetermined amounts of the resistance in circuit with one solenoid and cut out a proportional amount of the resistance from the other solenoid and thereby differentially energize the solenoids and move the armatures and adjustable electrode to predetermined stable positions and connect the electromagnetically operated means for releasing the retaining means in the circuit to release the armatures, and circuit breaking means connected in the circuit of the circuit closing means controlled by the movement of the armatures when moved to predetermined position to open the circuit of the solenoids and releasing means for the retaining means to permit the latter to move to armature retaining position.

7. Means to tune the receiving circuits of radio apparatus to resonance with the transmitted frequencies as claimed in claim 6, wherein the retaining means comprises a disk rotatable with the armatures and having notches in the periphery and a pawl normally urged to engage one of the disk notches, and the electromagnet means to release said retaining means adapted to move and retain said pawl out of engagement with the disk notches.

8. Means to tune the receiving circuits of radio apparatus to resonance with transmitted frequencies as claimed in claim 6, wherein the means to open the circuit of the solenoids comprises a cylinder rotatable with the armatures of electric conducting material electrically connected in the solenoid circuit and having a series of dielectric

- insets arranged in axially and circumferentially stepped relation to each other, and a series of contact members mounted to engage said cylinder, each contact member engaging the cylinder in alinement with a dielectric inset, and electrically connected in the solenoid circuit.
9. In means to tune the receiving circuits of radio apparatus to resonance with transmitted frequencies, a pair of spaced electrodes one of which is adjustable relative to the other, solenoids connected in circuit with and energized from a source of electricity, armatures connected to the adjustable electrode, each armature being associated with and actuated in opposite directions under the influence of a solenoid, a disk rotatable with the armatures and having notches disposed about the periphery in predetermined spaced relation, a detent pawl yieldingly urged toward the disk and into engagement with a disk notch, an electromagnet connected in circuit with the source of electricity and adapted to be energized to attract and release the pawl from the disk notch, a cylinder rotatable with the notched disk, said cylinder being of electric conducting material electrically connected in the circuit of the electromagnet and having dielectric insets arranged in axially and circumferential stepped relation to each other, and each dielectric inset being in radially opposed relation to a disk notch, contact members connected in the circuit of the electromagnet and having rubbing contact with the cylinder, and each contact member adapted to engage a dielectric inset, and controllable means interposed in the circuit of the electromagnet and solenoids to control the energization of the electromagnet and solenoids to release and actuate the armatures to a multiplicity of stable positions.
10. In means to effect predetermined tuning of the receiving circuits of radio apparatus to resonance with the transmitted frequencies, a pair of spaced electrodes, one adjustable relative to the other interposed in the circuit of the radio apparatus, solenoids connected in a circuit with and energized from a source of electricity, an armature associated with each solenoid and operatively connected with the adjustable electrode and movable under the influence of the solenoids in opposite directions, a series of electric resistance elements interposed in the circuit of each solenoid, a series of contact members, a terminal of each contact member being adapted to be manually connected in one side of the circuit of a series of the electric resistance elements, and means to periodically connect the opposite terminals of the contact members to the terminals of the solenoids opposite to the terminals connected to the resistance elements to differentially energize the solenoids and move the armatures and adjustable electrode in predetermined directions to a multiplicity of stable positions.
11. In means to effect predetermined tuning of the receiving circuits of radio apparatus to resonance with transmitted frequencies as claimed in claim 10, means interposed in the circuit of the series of contact members and the resistance elements adapted to be actuated by the movement of the armatures to selectively cut out of the solenoid circuit the connected contact member and stop the actuation of the armatures and adjustable electrode at a predetermined position.
12. In means to effect predetermined tuning of the receiving circuits of radio apparatus to resonance with transmitting frequencies, a pair of spaced electrodes one adjustable relative to the other interposed in the circuit of the radio apparatus, solenoids connected in a circuit with and energized from a source of electricity, an armature associated with each solenoid operatively connected with the adjustable electrode and movable under the influence of the solenoids in opposite directions, variable electric resistance interposed in the circuit of each solenoid, a series of electromagnetically operative contacts having terminals connected to different portions of the resistance, a series of contact members, a terminal of each contact member being adapted to be manually connected to a terminal of an electromagnet of each electromagnetically operative contact and the opposite terminals of said electromagnets connected to the source of electricity, and means to periodically connect the other terminals of said series of contact members to the terminals of the solenoids opposite to the terminals connected to the resistance to differentially energize the solenoids and move the armatures and adjustable electrode in predetermined directions to a multiplicity of stable positions.
13. Means to effect predetermined tuning of the receiving circuits of radio apparatus to resonance with transmitted frequencies as claimed in claim 10, wherein the series of contact members comprises a series of parallel strips of conducting material electrically connected to the resistance elements and having equidistantly spaced perforations, and a second series of conducting strips extended transversely of and in juxtaposed relation to the first series of strips and arranged with equidistantly spaced recesses in alinement with a peripheral portion of the perforations of the first strips, and pins of conducting material adapted to be inserted into said perforations to electrically connect predetermined strips in circuit with the resistance elements.
14. Means to effect predetermined tuning of the receiving circuits of radio apparatus to resonance with transmitted frequencies as claimed in claim 10, wherein the series of contact members comprises two parallel series of conducting strips with the strips of one series extended in juxtaposed relation to and transversely of the other series and adapted to be variably connected in electric circuit with each other, one of said series of strips being electrically connected to the resistance means and the other series having lateral extensions, and the periodical connecting means comprising a rotatable arm electrically connected to the terminals of the solenoids and the source of electricity and magnetized, said arm being actuated to periodically juxtapose the free end relative to the lateral extensions of the one series of contact strips and adapted to attract and engage said extensions to complete the electric circuit through the connected conducting strips and the solenoids.
15. In means to effect predetermined tuning of the receiving circuits of radio apparatus to resonance with transmitted frequencies as claimed in claim 12, means actuated by the movements of the armatures and interposed in the circuit of the electromagnets with the source of electricity adapted to open said circuit and stop the armatures at predetermined positions.
16. In means to effect predetermined tuning of the receiving circuits of radio apparatus to resonance with transmitted frequencies as

claimed in claim 12, means operative to normally prevent movement of the armatures, and an electromagnet interposed in the circuit of the electromagnets of the electromagnetically operative contacts and the source of electricity to release said means and permit movement of the armatures.

17. In means to tune the receiving circuits of radio apparatus to resonance with transmitted frequencies, a fixed electrode and an electrode spaced from and adjustable relative to the fixed electrode interposed in the circuit of the radio apparatus, electromagnetically operated means connected in a normally open electric circuit with a source of electricity and connected with and adapted to be differentially energized to move the adjustable electrode to predetermined positions relative to the fixed electrode, selectively operative means to close the circuit of and effect differential energization of the electromagnetically operated means and movement thereof and adjustment of the adjustable electrode

to predetermined stable positions, means automatically operative at the termination of a predetermined movement of the electromagnetically operated means and adjustable electrode to positively and releasably lock the same in predetermined actuated position, and electromagnetically operated means connected in a normally open electric circuit adapted when energized to release and hold said locking means in releasing position, and, the selectively operative means operative to close the circuit thereof when actuated to close the circuit of the electromagnetically operated means to actuate the electromagnetically operated means and adjustable electrode, and means to simultaneously open the circuits of the electromagnetically operated electrode adjusting means when the electrode has been adjusted to predetermined position and the circuit of the electromagnetically operated releasing means for the locking means and permit said locking means to assume its locking position.
